his Attorney,

UNITED STATES PATENT OFFICE.

CLARENCE L. BARNHART, OF FLINT, MICHIGAN.

CAR-MOVER.

SPECIFICATION forming part of Letters Patent No. 396,190, dated January 15, 1889.

Application filed June 15, 1888. Serial No. 277,233. (No model.)

To all whom it may concern:

Be it known that I, CLARENCE L. BARNHART, a citizen of the United States, residing at Flint, in the county of Genesee and State of Michigan, have invented a certain new and useful Improvement in Car-Movers, of which the following is a full, clear, and exact description.

This invention relates to that class of devices which are operated by hand to move railway-cars about a yard and elsewhere, and which are commonly designated "car-movers."

The object of the invention is to economize in the power necessary to utilize such devices. The invention consists in a hollow staff provided with a rotary gripping device peculiarly constructed to engage the rails of a track and operable by chain or link gearing within the staff and a crank-handle outside, whereby the gripping device is given a rotary motion on the rail, and thus propels the car, substantially as presently set forth and claimed.

In the accompanying drawings, illustrating my invention, in the several figures of which like parts are similarly designated, Figure 1 is a side elevation showing my car-mover in situation for use. Fig. 2 is a plan looking at the bottom. Fig. 3 is a longitudinal section. Fig. 4 is a bottom end view. Fig. 5 is a vertical cross-section of part of the gripping device, and Fig. 6 is a perspective view of the same with one of the knife-edges removed. Figs. 7 and 8 are cross-sections taken, respectively, in the planes of lines $x-x$ and $y-y$ of Fig. 2.

The letter a designates a tubular staff of suitable dimensions and strength. In one end is fitted a crotch, b , appropriately shaped to engage the end of a railway-car. As shown, this crotch is provided with a forked and shouldered shank to enter the tubular staff and is secured therein by screws $b'b'$. In the other end of this staff, whose walls may be made flat for this purpose, (see Figs. 2 and 7,) is arranged a sprocket-wheel, c . This sprocket-wheel turns with its shaft d , and this shaft extends outside the staff and receives on squared journals the halves e of the gripping device or gripper f , which halves are attached to the said shaft by nuts d' or in other

secure manner. Each part e has a hub, g , which fits in an opening, h , in the staff, such openings in opposite sides of the staff (see Fig. 7) thus forming bearings for the hubs g 55 and indirectly for the shaft d . The gripper has a series of fingers, e' , extending rather tangentially, and provided with knives or biting-surfaces e^2 , of steel or other hard metal, bolted, riveted, or otherwise fastened to the 60 fingers. As shown, the halves of the gripper are made as rights and lefts and are dished so as to spread or flare out from each other, and thus more effectually wedge and bite upon the rail, as indicated in Figs. 2 and 4. The 65 fingers of the gripper subserve an additional purpose in that they enable the mover to be used by running the gripper on the ground or a board instead of confining its use to the rails of the track. By making the gripper in 70 two parts it is much more economically manufactured, much more easily repaired, and much more easily got at for repairs than is the case with those structures heretofore designed where the gripper is solid and the staff 75 is divided or forked to receive it. A second sprocket-wheel, i , is fixed to turn with a squared shaft, j , which is supported in bearings in the staff a , and one end of this shaft j is provided with a crank-handle, k , whereby the 80 shaft j and sprocket-wheel i may be rotated. The shaft j or handle k may have a circular boss, k' , to fit as a journal in an opening, k^2 , in the staff, and the other end of this shaft has a circular nib finding a bearing in the other side 85 of the staff. The sprocket-wheels i and c are connected by a chain or link belt, l , for transmitting the motion of the former to the latter, and thereby rotating the gripper.

When the device is arranged as in Fig. 1, 90 by keeping the gripper hard on the rail and turning the crank the gripper will bite and advance upon the rail finger by finger, and so propel the car. One man can readily move a loaded car with one of my devices.

If desired, a handle may be placed on each end of shaft j , so as to permit two men to operate the device; but the gearing will suffice to enable one man to readily move a loaded car with the device constructed as shown.

The staff is hollow, so as to conceal the gearing and protect it from dust, the weather, and

other sources of injury; but it is within my invention to employ a solid staff with the gearing arranged thereon.

As indicated by the dotted lines in Fig. 3, 5 a train of gears may be interposed between the shafts *d* and *j* in order to augment the power.

What I claim is—

1. A car-mover composed of a staff, *a*, a crotch, *b*, in one end of such staff to engage a car, a gripper, *f*, supported upon a shaft which is borne by the other end of said staff, said gripper being composed of dished halves *e*, provided with hubs to receive the shaft, and 15 with fingers *e'*, having biting-edges *e²* thereon, which halves are independently and detachably fixed to the shaft, and gearing for im-

parting rotary motion to said gripper, substantially as and for the purpose described.

2. A rotary gripper composed of dished 20 halves *e*, provided with hubs *g*, and having the fingers *e'*, with knives *e²* fastened thereon, combined with a hollow staff having openings in its sides forming bearings for said hubs, a shaft to which said halves are independently 25 and detachably fixed, and operating-gearing for imparting rotary motion to said gripper, substantially as described.

In testimony whereof I have hereunto set my hand this 13th day of June, A. D. 1888.

CLARENCE L. BARNHART.
